SEPARATOR FOR MEAT AND PRODUCE

Alan J. Bacon, Alhambra, Calif.

Application May 10, 1954, Serial No. 30,408

Term of patent 14 years

(Cl. D11—1)

I claim:

The ornamental design for a separator for meat and produce substantially as shown.
